[57] ABSTRACT

A current mode type semiconductor logic circuit comprises at least one grounded-emitter transistor through which a power source is connected to the logic circuit. The output of the logic circuit is fed back to the grounded-emitter transistor through a feedback circuit. As a result, the variation in the output of the logic circuit can be controlled to a minimum even when the load of the logic circuit is varied.

SEMICONDUCTOR LOGIC CIRCUIT

BACKGROUND OF THE INVENTION:

The present invention relates to semiconductor logic circuits and more particularly to improvements in a current mode type semiconductor logic circuit comprising at least one input transistor to which an input signal is applied, and at least one reference transistor to which a reference signal is applied.

DESCRIPTION OF THE PRIOR ART

The semiconductor logic circuits used in high speed electronic computers are supposed to satisfy the requirements of high operating speed, high integration, and low power consumption.

The current mode type semiconductor logic circuit has most generally been in use as a high speed logic circuit in the prior art. This type of logic circuit consumes a large amount of power. To solve this problem, a direct-coupled type logic circuit has been proposed. This logic circuit, however, gives rise to many problems if it is used in a monolithic IC system.

SUMMARY OF THE INVENTION

An object of the present invention is to provide a semiconductor logic circuit operable consuming very little power and capable of controlling the output voltage variation to a minimum even if a partial impedance variation occurs in the load circuit network.

Another object of this invention is to provide a semiconductor logic circuit capable of compensating for the dispersion of circuit elements and for variations in operating conditions.

Still another object of this invention is to provide a semiconductor logic circuit capable of driving a transmission line by its collector output even when the logic circuit is fabricated in a monolithic IC system.

Briefly, the above objects are realized in a current mode type semiconductor logic circuit in which a power source is connected to the logic circuit by way of at least one emitter-grounded transistor, and the output of the logic circuit is fed back to the base of the emitter-grounded transistor by way of a feedback circuit.

BRIEF DESCRIPTION OF THE DRAWING

FIG. 1 is a circuit diagram showing the fundamental composition of the logic circuit of this invention, and

FIGS. 2, 3(a), 3(b), 4 and 5 are circuit diagrams showing logic circuits embodying this invention.

DESCRIPTION OF THE PREFERRED EMBODIMENTS

Referring to FIG. 1, there is shown the fundamental arrangement of the logic circuit of this invention, wherein the references T₁₁ through T_{1n} denote transistors respectively, to which an input signal V_{i(i)} is applied, T₂ a transistor, to which a reference voltage V_{BB} is applied, and T₃ a grounded-emitter transistor, through which an emitter source voltage V_{EE} is applied to a common emitter terminal E of said transistors T₁₁ through T_{1n} and T₂. The output of a load circuit 1 of the logic circuit comprising transistors T₁₁ through T_{1n}, T₂ is fed back to the base of grounded-emitter transistor T₃ via a feedback circuit 2.

In this logic circuit, as is well-known, an OR output or its inverted output is obtained at the output terminal

3 according to the result of comparison between the reference voltage V_{BB} and the input signal applied to the base of one of the transistors T₁₁ through T_{1n}. According to the teaching of this invention, the output V_{o(j)} is fed back to the base of the grounded-emitter transistor, thereby minimizing any variation in the output voltage of the logic circuit, even if the impedance is partially varied in the load circuit 1. Further objects and advantages of the invention will be best understood 10 by reference to the following specification of illustrative embodiments.

Unless specifically noted, it is assumed that the current amplification factor h_{FE} of the transistor used is sufficiently large, the forward voltage drop V_{BE} across the base and emitter is about 0.8V, and the transistor is operated unsaturation until its base-collector junction is biased forward at about 0.5V. This condition is almost fully satisfied in the ordinary silicon epitaxial planar transistor for logic circuits.

EXAMPLE 1

Referring to FIG. 2, there is shown a logic circuit embodying this invention wherein the resistance values of output resistors R₁ and R₂ are determined to be sufficiently large compared with those of collector resistors R_{CN} and R_{CP} and, hence, a voltage of approximately half the output voltage is produced at the connection point 4 of R₁ and R₂ when transistor T₁ or T₂ is conducting. This voltage is applied to the base of a transistor T₄. The emitter of transistor T₄ is connected to the base of a grounded-emitter transistor T₃, and an emitter source voltage V_{EE} is applied to the emitter of transistor T₄ by way of resistor R₃.

Because the base-emitter voltage V_{BE} of transistors T₃ and T₄ is constant, the voltage V_K at the connection point of the output resistors R₁ and R₂ is given as

$$V_K = V_{EE} + 2V_{BE} = -1.8V + 2 \times 0.8V = -0.2V \quad (1)$$

Therefore, the output voltage V_o at the collector on the side of whichever transistor T₁ or T₂ is conducting is expressed as

$$V_o = 2V_K = 2(V_{EE} + 2V_{BE}) = -0.4V \quad (2)$$

In this current mode type semiconductor logic circuit comprising transistors T₁ and T₂, the output voltage V_o is determined essentially by the emitter source voltage V_{EE} on condition that the resistance values of the load resistors R_{CN} and R_{CP} are sufficiently smaller than those of the output resistors R₁ and R₂, even if small variations occur in the value of the load resistors R_{CN} and R_{CP}. Under this condition, therefore, the output voltage can be kept minimally affected by the variation in the load impedance. By suitably determining the value of a capacitor C inserted in the base of transistor T₄, an output voltage with the desired waveform can be obtained.

EXAMPLE 2

In FIG. 3(a), an output resistor R₁ is connected across the collectors of transistors T₁ and T₂, and one end of resistor R₁ is connected to the base of a grounded-emitter transistor T₃. In this circuit, when the transistor T₁ is in the conducting state, the base current of grounded-emitter transistor T₃, which current flows via the output resistor R₁, is sufficiently small. Therefore,

the collectors of transistors T_1 and T_2 and the base of transistor T_3 are at nearly the same potential.

Hence, the output voltage V_o obtainable at conduction of transistor T_1 is given as

$$V_o = V_{EE} + V_{BE} = -0.4V$$

When the transistor T_2 is conducting, its collector load becomes $R_{CN} + R_1$, and the collector current is far smaller than when the transistor T_1 is conducting. As a result the output voltage V_o becomes almost zero. In this embodiment, although only the inverted output is obtainable, a smaller number of circuit elements suffices than in the embodiment, Example 1. Furthermore, because V_{BE} is small and the mean current to flow at switching transistors T_1 and T_2 is small, the necessary power consumption is reduced.

EXAMPLE 3

This example, as shown in FIG. 3(b), is similar to Example 2, except that this circuit makes an "ON" output available.

EXAMPLE 4

This example, as shown in FIG. 4, is a modification of Example 1. In FIG. 4, the input signal is applied to the base of transistors T_{01} through T_{0n} . This circuit is characterized by its capability of delivering a large amplitude output.

EXAMPLE 5

This example is shown in FIG. 5 wherein a stabilizing circuit using an emitter source voltage V_{EE} provided as in Example 2 is employed to compensate for dispersion or temperature variation in V_{BE} , h_{fe} , etc., of the transistors. The aim of this stabilizing circuit is to make the output voltage of transistor T_1 equal to the voltage determined only by the value of the source voltage V_E and the ratio of the values of resistors R_{58} and R_{59} when transistor T_1 is in the conducting state.

In the stabilizing circuit (indicated by the dotted line), the output of a differential amplifier comprising transistors T_{53} , T_{54} , resistors R_{53} and R_{54} is applied to a transistor T_{51} via a transistor T_{52} and a resistor R_{51} . Therefore, the collector voltage of transistor T_{51} (i.e., the emitter source voltage V_{EE}) can be made equal to the emitter voltage of transistor T_{56} . Hence, if the values of transistors T_{56} and T_3 are determined to be nearly the same, and likewise the values of resistors R_{57} and R_1 , and also the value of resistor R_{56} is determined so that the collector current of T_3 is nearly equal to that of transistor T_{56} , the emitter voltage of transistor T_{56} , namely the emitter source voltage V_{EE} , is stabilized. The purpose of the transistor T_{55} is to approximate the operating conditions of two transistors T_{56} and T_3 .

It is to be noted that resistance and voltage values indicated in the drawings are only for reference; the invention is not limited to those values. The transistors used in the foregoing embodiments may be of either npn or pnp.

In the conventional current mode type semiconductor logic circuit fabricated in a monolithic IC system, the ratio of resistance values can be relatively accurately controlled within the same monolithic circuit. Hence, the accuracy of the output voltage can be controlled to be fairly high if the emitter resistor and collector load resistor are formed in the same monolithic circuit. In a monolithic circuit, however, it is difficult

to reduce the dispersion of the absolute value of resistance. When the collector load resistor is not included in the same monolithic circuit but is connected thereto externally, the accuracy of the output voltage is significantly lowered. This will result in saturation of the circuit, to lower the operating speed and reduce the noise margin. In a large electronic computer, it is necessary to minimize the delay caused by elongated length of a transmission line. To this effect the distributed line for transmission must be terminated by a resistor whose characteristic impedance is nearly equal to that of the distributed line network. In such case it is apparently impossible for one monolithic circuit to include both the emitter resistor and the collector load resistor; here the aforementioned problem is inevitable.

Whereas, according to this invention, as described above, variations in the output voltage can be controlled to a minimum even when partial impedance variation takes place in the load circuit network of the collector. Thus, in other words, the invention enables the use of a monolithic IC system to manufacture efficient logic circuits free of the prior art problems.

I claim:

1. In a current mode type semiconductor logic circuit having at least one input transistor to which an input signal is applied, at least one reference transistor to which a reference signal is applied, said input transistor being adapted so as to operate when said input signal is larger than said reference signal, a power source, and a load circuit connected to said input and reference transistors for deriving out therefrom an output signal from said input and reference transistors, the improvement which comprises at least one grounded emitter transistor through which said power source is connected to said input and reference transistors, and a feedback circuit connected between said load circuit and said grounded emitter transistor for feeding back said output signal thereto.

2. A logic circuit according to claim 1, wherein said feedback circuit comprises output resistor means connected between the outputs of said input and reference transistors, and a grounded collector transistor connected between said output resistor means and the input of said grounded emitter transistor.

3. A logic circuit according to claim 1, wherein said feedback circuit comprises an output resistor connected between the outputs of said input and reference transistors, and said grounded emitter transistor connected to said output resistor.

4. A logic circuit according to claim 1, which comprises a stabilizing circuit connected between said grounded emitter transistor and said power source for stabilizing the emitter voltage of said grounded emitter transistor.

5. A current mode type semiconductor logic circuit comprising:

at least one input transistor to which an input signal is to be applied;

a reference transistor to which a reference signal is to be applied, said input and reference transistors being coupled together in common for receiving a source of power;

a load means connected to each of said input and reference transistors for generating a signal when said input signal is larger than said reference signal; a power coupling transistor, having its emitter connected to said source of power, connected to the

common connection point of said input and reference transistors for coupling thereto said source of power; and
means connected between said load means and power coupling transistor, for feeding back the output of said load circuit to said power coupling transistor, so as to compensate for variations in the output of said logic circuit.

6. A current mode type semiconductor logic circuit according to claim 5, wherein said feedback means comprises means for resistively connecting the output of said load means to said power coupling transistor.

7. A current mode type semiconductor logic circuit according to claim 6, wherein said feedback means comprises first and second resistors connected in series between said input and reference transistor outputs, and a feedback transistor coupling the common connection of said first and second resistor to said power coupling transistor.

8. A current mode type semiconductor logic circuit according to claim 7, wherein said at least one input transistor comprises a first input transistor to which said input signal is applied and a second input transistor connected to the output of said first input transistor and to said reference and said power coupling transistor, the output of said second input transistor being connected to said load means.

9. A current mode type semiconductor logic circuit according to claim 6, wherein said feedback means comprises a resistor connected between said input and reference transistors and a conductor for coupling the output of one of said input and reference transistor to

said power coupling transistor.

10. A current mode type semiconductor logic circuit according to claim 9, wherein said conductor is connected to said input transistor.

11. A current mode type semiconductor logic circuit according to claim 9, wherein said conductor is connected to said reference transistor.

12. A current mode type semiconductor logic circuit according to claim 8, further comprising a stabilizing circuit connected between said power source and said power coupling transistor for compensating for variation in the characteristics of said transistors.

13. A current mode type semiconductor logic circuit according to claim 12, wherein said stabilizing circuit comprises a differential amplifier circuit having one of its inputs coupled to said power coupling transistor and the other coupled to a compensating power supply circuit, the output of said differential amplifier being connected through a pair of transistors to said power coupling transistor.

14. A current mode type semiconductor logic circuit according to claim 13, wherein said compensating power supplying circuit comprises a pair of transistors connected in series, the characteristics of one of which corresponds substantially to said power coupling transistor and a biasing transistor connected between said power source and said one transistor of said pair for maintaining the collector current thereof substantially the same as the collector current of said power coupling transistor.
